UNITED STATES PATENT OFFICE.

LITFALLAH G. SABBAG, OF EAST BOSTON, MASSACHUSETTS.

PERMUTATION-LOCK.

1,356,314.

Specification of Letters Patent. Patented Oct. 19, 1920.

Application filed May 9, 1918. Serial No. 233,595.

To all whom it may concern:

Be it known that I, LITFALLAH G. SABBAG, a citizen of the United States of America, and resident of East Boston, in the county 5 of Suffolk and State of Massachusetts, have invented new and useful Improvements in Permutation-Locks, of which the following is a specification.

This invention relates to keyless or permutation locks, principal objects being to provide a lock of this class of durable, strong and simple construction, efficient to prevent unauthorized opening and adapted to be used instead of padlocks employed to 15 prevent unauthorized removal of or of parts from automobiles, boats, bicycles, and other exposed movable property.

In the accompanying drawings,

Figure 1 is a longitudinal section of the 20 lock showing parts in elevation;

Fig. 2 is an elevation from the left of Fig. 1;

Fig. 3 is a view in plan;

Fig. 4 is a perspective view of one of the 25 permutation tumblers removed.

The lock comprises a frame 1 preferably as shown consisting of an open U-shaped piece bent from a rectangular bar of steel, brass, or other metal, having therein at 2, 30 3, aligned bores adapted to receive the straight round bolt 4 which may be curved at 5 to constitute a shackle projecting at one side of the part 1 and adapted to be turned out of the plane of Fig. 1 to open 35 the same when the bolt is in the open position illustrated in Fig. 1. The shackle 5 terminates at 6 in a portion parallel with the bolt 4 and adapted to enter a bore 7 when the lock is closed.

40 The bolt 4 is provided with a key or pin 8 adapted just to clear the frame 1 when the lock is fully open and to enter a key seat 9 in the frame 1 when the lock is closed. The bolt 4 is also provided with a stop pin 45 10 adapted to prevent farther movement of the bolt 4 through the frame 1 more than enough to clear the key 8 beyond the frame.

A plurality of locking tumblers 12 are strung on the bolt 4 and adapted to coöperate with lugs 14 integral with or fast in the bolt 4 at uniform distances apart equal to the thickness of the locking tumblers 12. The tumblers 12 may be and preferably are hexagonal bodies, conveniently being 55 formed from such punchings as are used to make hexagonal nuts but of course may

be round, or polygons other than hexagons. The central bore 15 of the tumblers 12 fits on and is rotatable on the bolt 4. The right hand face of each tumbler 12 is circularly 60 recessed at 16 to provide a free space for the rotation of the lugs 14. Each tumbler 12 is provided in a random relation to the faces of its polygonal outer surface with a key-way 17 adapted to receive the lugs 14, 65 when all of the key-ways 17 are in alignment. A preferred arrangement of the keys 17 relative to the surfaces of the hexagonal or other polygonal periphery of the parts 12 places some of them in line with the 70 meeting faces of the outer surfaces and some of them in line with the middle of one face of each locking tumbler.

Each face of each tumbler bears a number, letter or sign.

The frame 1 may have a counter-sunk 75 hole 20 for a wood screw for attachment to a door as shown in dotted lines at 21, the bolt 4 then taking into a hole 22 in the door frame or jamb.

The operation of the device will now be apparent. A particular order as read by arrangement in line with the upper flat surfaces of the frame 1 of the tumblers 12 which may readily be turned by hand, is 85 necessary to bring the key-way 17 into line with the lugs 14. If any tumbler is out of the position determined by this order the bolt 4 can not be moved longitudinally through the series of tumblers which preferably are held against each other with some friction by the spring of the slightly resilient bent metal frame 1. In the arrangement shown the tumblers 12 being hexagonal and numbered from 1 to 6, each of them has twelve possible positions of which one only is that for the open position of the lock. For instance, as shown in the figure the combination is 3— $\frac{1}{2}$ —5—3.

When the lock has been opened the revolution of the bolt 4 carries the tumblers with it in the order of their combination so that the lock may be closed again without having to reset the combination.

What I claim is:

1. A permutation lock having therein a series of rotatable locking tumblers, a bolt arranged at the center of rotation of said tumblers, means fixed on the bolt adapted to pass each tumbler at one rotative position 110 only of said tumbler, a resilient frame adapted to hold in endwise frictional con-

tact a series of the tumblers strung on the bolt in contacting relation with each other, and means adapted to prevent the rotation of the bolt in the frame except when the bolt 5 is longitudinally displaced with respect to the frame and the tumblers.

2. A permutation padlock comprising a U-frame, a shackle bolt adapted to be longitudinally and rotatably moved in bores in 10 said frame, a series of tumblers strung on the bolt between the lugs of the frame, means fixed on the bolt for contact with each

tumbler except when the tumbler is in a certain rotative position, to prevent longitudinal movement of the bolt except when each of the tumblers is rotated to a definite position, and means for locking the tumblers to the bolt to rotate therewith when longitudinal movement of the bolt is permitted.

Signed by me at Boston, Massachusetts,
this seventh day of May, 1918.

LITFALLAH G. SABBAG.
